UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

AUTOMATIC FILLING-REPLENISHING LOOM.

Application filed February 16, 1923. Serial No. 619,498.

To all whom it may concern:

Be it known that I, ALONZO E. RHOADES, a citizen of the United States, and resident of Hopedale, county of Worcester, State of Massachusetts, have invented an Improvement in Automatic Filling-Replenishing Looms, of which the following description, in connection with the accompanying drawing, is a specification, like characters on the drawing representing like parts.

This invention relates to automatic filling replenishing looms and more particularly to means for preventing the ends extending from the fresh filling carriers as they are successively discharged from the magazine into the running shuttle from being carried into the shed.

The object of the invention is more particularly to provide means for taking care of such filling ends when these ends are secured to the exterior of the hopper as, for example, in that type of construction shown in the patent to Stimpson, 834,945 granted November 6, 1906.

A great deal of attention and inventive effort have been devoted to the care of the filling ends left by the operation of automatic filling replenishment. While the greatest difficulty is experienced in the care of the filling end extending from the filling carrier discharged from the shuttle there is, nevertheless, a great deal of difficulty experienced with the filling end running from the fresh filling carrier to the point at which it is secured and held so as to enable the first pick to be made properly. The present invention presents a simple effective and accurate means for insuring that this filling end shall not be caught by the shuttle or the working filling and be carried or thrown into the shed.

The nature and object of the invention will appear more fully from the accompanying description and drawings and will be particularly pointed out in the claims.

The general nature of the construction and operation of the automatic filling replenishing loom being well known and familiar to those skilled in the art and those features thereof with which the present invention is particularly associated being illustrated and described in the aforesaid patent to Stimpson it is unnecessary here to illustrate and describe in detail anything more than those

elements of the loom involved in a preferred embodiment of the present invention.

In the drawings:

Fig. 1 is an inner end view of the hopper stand and hopper with a portion of the breast beam and lay shown in cross section;

Fig. 2 is a view in front elevation of the hopper stand with the hopper shown chiefly in central vertical cross section;

Fig. 3 is a top plan view of the main portion of the hopper stand.

The breast beam 1 of the loom is shown as supporting at the replenishing or right hand end the hopper which carries the supply of fresh filling carriers. The hopper stand includes a base 2 bolted to the breast beam and an upright or vertical flanged plate 3 which forms the support for the rotary hopper and other working parts concerned in the replenishing operation. This plate 3 at its upper central portion presents the hub 4 in which is mounted the spindle or shaft 5 upon which the hopper rotates. The plate 3 slopes downwardly forwardly and rearwardly from this hub so as to leave exposed the main portion of the exterior of the hopper and enable the operator readily to secure in place the filling ends extending from the filling carriers in the hopper. At its forward portion the plate 3 is provided with a hub 6 carrying the shaft or stud 7 on which the usual transfferer 8 is mounted so that when the operation of filling replenishment takes place the transfferer 8 will swing downwardly and its head 9 will carry the fresh filling carrier from the hopper down into the shuttle 10 on the lay 11 therebeneath and eject therefrom the substantially exhausted filling carrier.

The hopper in the form illustrated comprises the usual generally circular disks 12 and 13 secured to or forming part of the central sleeve 14 journaled on the spindle 5. At the interior of the hopper and on the interior face of the disk 12 is provided adjacent the periphery the usual circular series of seats 15 in which are mounted the butts 16 of the fresh filling carriers 17. These filling carriers extend parallel with the axis of the hopper and their tips 18 are usually supported in tip holders 19 movably mounted on the end disk 13.

This type of hopper is arranged to pro-

vide the minimum length of filling end extending from the securing means so that there will be as little waste of filling as possible. The filling end must be held when a 5 fresh filling carrier is discharged from the hopper so that the first pick will be laid properly in and beaten into the shed and there must accordingly be some waste, but with this type of hopper the waste is minimized. In this type of construction a circular series of filling end holders is mounted on the exterior of the hopper as on the exterior surface of the disk 12. Preferably and for convenience this series of end holders 10 comprises one for each two filling carriers because two filling ends may readily be connected to a single end holder. For this purpose each filling end holder 20 is shown as a pair of spring pressed clamping disks 15 between which the filling end is wound by the operator. These disks are supported on studs 21 secured in arms 22 projecting from a flange ring 23 secured to the exterior face of the hopper disk 12. In this convenient arrangement each filling end holder 20 is arranged on a radius extending between each adjacent pair of filling carrier seats 15.

One of the principal features of the invention resides in the provision of separating 20 positioning wings herein shown as rhomboidal-shaped flanges 24 projecting from the exterior of the hopper disk 12 and so located as to insure the peculiar and desired position of the runs of filling ends extending 25 from the respective filling carriers to the respective filling end holders. These positioning wings or flanges are so located and arranged that each run of filling extends from the hopper periphery to its end holder 30 in the direction of rotation of the hopper and forms a substantial angle with that radius of the hopper which passes through the point where the run of filling crosses the hopper periphery.

When the filling carriers are placed in the hopper the filling 25 is led by the operator around a pin 26, located for example on the corresponding tip holder 19 and then back through a notch 26 in the hopper periphery 35 in line with the seat in which the butt of the filling carrier rests. This provides the necessary slack in the filling to avoid breakage when transfer takes place. The operator then carries the filling end from the notch 26 down to and winds it about the proper end holder 20 thus securing it in place. The rhomboidal projecting flanges 24 which constitute the separating and positioning wings in this invention are so located that the operator can only position the run of filling 25 extending from the notch 26 in the periphery to the end holder 20 in the desired manner. That is this run of filling 40 must because of the location of the separating positioning wings extend in the di-

rection of rotation of the hopper and must lie at a substantial angle with that radius of the hopper extending through the notch 26.

Consequently when transfer takes place 70 and the fresh filling carrier is discharged by the transerrer 8 into the shuttle the filling end extending therefrom is attached to a positioning device 20 which has moved well forward so that when the filling end is cut, 75 as by the usual temple thread cutter, and left hanging it depends at a point well forward of the lay and in a position where it cannot be caught by the shuttle, the working filling or a moving part of the loom and be 80 thrown or carried into the shed.

In order further to assist in this position of the depending end a further provision is made in the structure of the hopper stand. The hopper stand is usually provided with a flange 27 projecting beneath the hopper forward of the position where the discharge of the fresh filling carrier from the hopper takes place. This flange 27 has riveted or bolted thereto at 28 a plate 29 turned upward at its rear end to constitute a fixed abutment 30 against which the filling carrier is guided as it is transferred into the shuttle.

In this invention a slot 31 is formed in the flange 27, preferably flared at its mouth, and extending forwardly from the rear edge of the flange and in the path of the filling end depending or hanging from the end holder 20. This depending end as it is carried forwardly by its attachment to the hopper consequently passes into the slot 31 which thus assists in allowing it to move well forwardly out of the way after transfer takes place.

The invention, therefore, by the peculiar arrangement and position of the separating and positioning flanges and by means of the slot in the flange of the hopper stand ensures that the filling ends left depending from the filling end holders after transfer has taken place shall move to a position where they cannot be caught or thrown into the shed and form an imperfection in the cloth.

Having thus described the invention what is claimed as new and desired to be secured by Letters Patent, is:

1. An automatic filling replenishing loom comprising a hopper stand, a hopper rotarily mounted in the stand, a circular series of seats at the interior of the hopper to receive and support the fresh filling carriers, a circular series of filling end holders on the exterior of the hopper, and separating positioning wings projecting from the hopper exterior, between the periphery and the circular series of end holders, and located to ensure that each run of filling from the hopper periphery to its end holder shall ex- 130

tend in the direction of rotation of the hopper and shall form a substantial angle with that radius of the hopper passing through the point where the run of filling crosses the 5 hopper periphery whereby the filling end extending from the end holder after transfer of the corresponding filling carrier will be carried well forwardly out of the way.

2. In an automatic replenishing loom the 10 construction defined in claim 1, together with a flange projecting from the hopper

stand beneath the hopper forward of the point of discharge of the filling carriers, and presenting an elongated slot extending forwardly from its rear edge and in the path 15 of a filling end hanging from the end holder on the hopper to permit the said hanging end to move well forwardly out of the way after transfer takes place.

In testimony whereof, I have signed my name to this specification.

ALONZO E. RHOADES.
